UNITED STATES PATENT OFFICE.

CLARENCE E. FORSYTHE, OF MILWAUKEE, WISCONSIN.

SAFETY-CATCH FOR CUFF-LINKS.

1,353,525.

Specification of Letters Patent. Patented Sept. 21, 1920.

Application filed May 11, 1917, Serial No. 167,959. Renewed August 9, 1919. Serial No. 316,488.

To all whom it may concern:

Be it known that I, CLARENCE E. FORSYTHE, a citizen of the United States, residing at Milwaukee, in the county of Milwaukee and State of Wisconsin, have invented certain new and useful Improvements in Safety-Catches for Cuff-Links; and I do hereby declare the following to be a full, clear, and exact description of the invention, such as will enable others skilled in the art to which it appertains to make and use the same.

This invention relates to a safety catch which is particularly designed for use in connection with bar cuff links or buttons, for preventing the loss of the cuff buttons and the primary object of the invention is to provide a safety catch as specified, which is constructed of a single piece of resilient material, bent to form a cuff link bar gripping portion, and a cuff gripping portion, so that in case the cuff button should become loosened from a shirt cuff, it will be held by the safety catch.

With the foregoing and other objects in view, this invention consists in such novel features of construction, combination and arrangement of parts as will be hereinafter more fully described, illustrated in the accompanying drawing and claimed.

In describing the invention in detail, reference will be had to the accompanying drawing wherein like characters designate like and corresponding parts throughout the several views, and in which:

Figure 1 is a side elevation of the improved safety catch illustrating the same immediately after it has been mounted over the bar of a cuff button, and illustrating in dotted lines the position of the catch prior to its connection with a cuff button.

Fig. 2 is a side elevation illustrating the normal position of the catch when in use, and

Fig. 3 is a detail perspective view of the catch.

Referring more particularly to the drawing, 1 designates the inner surface of the inner side of an ordinary shirt cuff, which is provided with the usual type of button-hole 2, through which the bar 3 of a cuff button extends. The safety catch structure, generically indicated by the numeral 5 is positioned against the inner side of a shirt cuff and it is constructed of a single strand of resilient wire or if it is preferred, it

may be constructed of a single strand or length of a resilient rectangularly shaped bar, this feature being left to the desires of the person manufacturing the same. The catch 5 comprises a straight portion or arm 6, one end of which is bent at right angles thereto as shown at 7, and looped to form a substantially U-shaped cuff edge gripping portion or clip 8. A straight length or second arm 9 projects outwardly from the upper end of the leg 10 of the U-shaped cuff edge gripping portion 8 and it lies substantially parallel to the straight portion 6, being adapted for positioning upon the opposite side of the cuff section from the straight portion 6 for gripping the cuff between the straight portion 6 and the straight portion 9. The straight portion 6 is bent inwardly as shown at 11, to provide a hump, against which the inner terminal 12 of the length of wire rests. The length of wire is bent, outwardly of the hump 11 to form substantially a semi-circle, as indicated at 13, and further to provide a straight portion 14 which connects a second semi-circular portion 15 to the semi-circular portion 13. The end of the semi-circular portion 15 which is remote from the straight portion 14 is connected to a relatively short straight portion 16 which is held in engagement with the straight portion 6, by the resiliency of the material of which the catch is formed and the semi-circular portions 13 and 15. The terminal 12 of the strand of wire or other material is connected to the straight portion 16 by an angular portion 17, and it is bent to form a substantially semi-circular portion which surrounds a portion of the bar 3 of a cuff button as clearly shown in Figs. 1 and 2 of the drawing.

A head structure 20, which is identical in all respects to the head composed of the semi-circular portions 12, 13, and 15 of the straight portions 14 and 16, and the angle portion 17, is formed upon the end of the straight portion 9. The head 20 is positioned in alinement with the head formed upon the straight portion 6, and it grips the shank of the cuff button at the inner surface of the inner side of the cuff 1, while the head formed upon the straight portion 6 grips the shank of the cuff button at the outer surface of the inner side or portion of the cuff 1.

The parts 12, 13, 14, 15 and 16 of each of the arms 6 and 9 provide spring hooks

adapted to embrace the shank 3 of the cuff button. Owing to the formation of the hooks, and as the parts 16 thereof engage the arms 6 and 9, it is impossible for the 5 hooks to be accidentally disconnected from the shank 3 of the cuff button.

The preferred manner of applying the safety catch may be stated to be as follows:

The safety catch is first positioned upon 10 the inner fold of the cuff so as to arrange the arm 6 and its hook, and the arm 9 and its hook, on opposite sides of said fold. The safety catch is then moved into the position indicated by the dotted lines in Fig. 1 of the 15 drawing to enable the hooks to be engaged with the shank 3 of the cuff button by moving the safety device from the dotted line position to the full line position of said figure of the drawing. The safety catch is 20 then swung on the shank 3 of the cuff button to position the clip 8 in engagement with the outer edge of the inner fold of the cuff, as illustrated in Fig. 2 of the drawing. The safety catch is held in this position by 25 the clip 8, and when it is in this position the arm 6 and its hook lie in close engagement with one side of the cuff fold and the arm 9 and its hook lie in close engagement with the other side of the cuff fold, and in 30 view thereof the safety catch will not be engaged by the sleeve when putting on or taking off the coat.

In the event that the small head of the cuff button should work through the button hole in the inner fold of the cuff, the safety catch would prevent such head from working through the button hole in the outer fold of the cuff. Should both heads of the cuff button work through both button 35 holes of the cuff, the safety catch would be moved on the cuff until the clip 8 reached the button hole in the inner fold of the cuff. As the clip 8 closes the arms 6 and 9 at one 40 end of the safety device, as the shank 3 of the cuff button closes the arms at the other end of the safety catch, as the arms are located on opposite sides of the cuff fold, and as one of the hooks and the arm carrying that hook is pulled through one of the button 45 holes of the cuff when both heads of the cuff button work through both button holes of the cuff, it should be apparent that the cuff button would not be lost but would be connected to the cuff by the safety catch.

50 It should be apparent that I provide a safety catch which may be readily and quickly applied and which will absolutely prevent the loss of a cuff button. The safety catch is simple and durable, and it 55 may be manufactured and sold at a comparatively low cost.

In reducing the invention to practice, certain minor features of construction, combination and arrangement of parts may necessitate alterations to which the patentee is

entitled provided such alterations are comprehended within the scope of what is claimed.

What is claimed is:

1. A safety catch for cuff buttons composed of a single piece of material including a straight portion, said piece of material bent to form a substantially semi-circular portion at one end of said straight portion, and further bent to form second 70 and third semi-circular portions, said third semi-circular portion adapted for engagement with the bar of a cuff button, and being connected to said second semi-circular portion by an angled and straight portion, 75 said last named straight portion adapted to engage said first named straight portion for forming a closure for the mouth of the space between the angled portion and the body portion for preventing the accidental removal of the catch from the bar of a cuff button.

2. A safety catch for cuff buttons composed of a single piece of material including a straight portion, said piece of material bent to form a substantially semi-circular portion at one end of said straight portion, and further bent to form second and third semi-circular portions, said third semi-circular portion adapted for engagement with the bar of a cuff button, and being connected to said second semi-circular portion by an angled and straight portion, 90 said last named straight portion adapted to engage said first named straight portion for forming a closure for the mouth of the space between the angled portion and the first named straight portion for preventing the accidental removal of the catch from the bar of a cuff button, the end of said first 95 named straight portion remote from said cuff button on bar gripping portion being bent to form a substantially right angularly disposed U-shaped portion and a third straight portion parallel to said first named straight portion, said U-shaped portion adapted for gripping the edge of a shirt cuff and said third straight portion adapted for coacting with said first named straight portion for gripping a shirt cuff and holding the catch attached thereto.

3. A safety catch for cuff buttons comprising a pair of arms, a hook carried by each arm in one end of the catch for engagement with the shank of the cuff button, and a cuff fold engaging clip connecting the arms at the other end of the catch and arranged at an angle to the arms.

In testimony whereof I affix my signature in presence of two witnesses.

CLARENCE E. FORSYTHE.
